E.D. Loveridge, of Buffalo, N.Y.
Letters Patent No 1837-dated Nov. 3, 1868.

Design for a Bottle.

The schedule referred to in these Letters Patent and making part of the same.

Dec. 1837

To all whom it may concern:

Be it known that E. Dexter

Loveridge, of the City of Buffalo, and State of New York, have invented a new and original Design for a Glass Bottle, for containing, holding, and vending Loveridge's celebrated "Wahoo Bitters," and I do hereby declare that the following is a full and exact description thereof, reference being made to the accompanying drawings and representations, making a part of this specification.

The general form of the bottle on its exterior surface, may be described as having a square base and rectangular sides, and made tapering from the upper part of the rectangle to its neck &c. as shown in the drawings.

Fig. 1, represents the front side of the bottle. Upon the tapering part thereof is formed in the glass the figures "1863," and upon the plane surface of the rectangle, a printed label is posted, which label is distinguished by the words, "The great Indian Beverage, Loveridge's celebrated Wahoo Bitters."

Below these words is the figure of an Indian Chief, and below the figure of the Indian Chief, is other printed matter descriptive of the virtue of the bitters, which printed matter may be varied, and is not deemed a part of the design. Below this printed matter appears other words name and figures, as follows, - "E. Dexter Loveridge, Sole Manufacturer and Proprietor, Buffalo, N.Y. D.W.D. 1863. - X X X."

Fig. 11, represents the second or reverse side of the bottle. Upon the plane surface of the rect-

Dec. 1837

angle is represented the American Eagle formed in the glass. Below this Eagle, a printed label is posted which is headed as follows: "D. W. D-1863-XXX-Proclamation."

Below the word "proclamation" is other printed matter which may be varied and is not deemed a part of this design.

Below this printed matter appears the words - "E. Dexter Loveridge, Buffalo, N.Y."

Upon the plane surface of the tapering part is to be formed in the glass, words and figures indicating the date of this patent when granted.

Fig. 3, represents the third side of the bottle. Upon the plane surface of the rectangle is represented the name and words as follows - "E. Dexter Loveridge, Wahoo Bitters", which are formed in the glass, and upon the tapering part is represented the letters "D. W. D." which are formed in the glass.

Fig. 4, represents the fourth side of the bottle. Upon the plane surface of the rectangle is represented and formed in the glass the name and words as follows - "E. Dexter Loveridge"

"Wahoo Bitters", and upon the tapering part is represented and formed in the glass the letters "XXX".

What I claim as my invention, and desire to secure by Letters Patent is, The Design for a glass Bottle substantially as herein described (with or without the labels attached) for the purposes set forth.

Witnesses,
